UNITED STATES PATENT OFFICE.

ARTHUR R. ROSAMOND, OF LARAMIE, WYOMING, ASSIGNOR, BY DIRECT AND MESNE ASSIGNMENTS, TO DORIS E. SODEN, OF KANSAS.

ELECTRIC TIME-SWITCH MECHANISM.

1,421,833.

Specification of Letters Patent.

Patented July 4, 1922.

Application filed June 10, 1921. Serial No. 476,482.

To all whom it may concern:

Be it known that I, ARTHUR R. ROSAMOND, a citizen of the United States, residing at Laramie, in the county of Albany 5 and State of Wyoming, have invented certain new and useful Improvements in Electric Time-Switch Mechanism, of which the following is a specification.

This invention relates to electric switches 10 for automatically closing and opening electric light circuits at times controlled by clock mechanism.

According to my invention I provide improved means whereby an electric light circuit may be automatically closed to turn on the electric lights at any desired time and may then without further attention be automatically opened to turn off the lights at a predetermined time. The invention is 15 especially applicable to lights in stores and other business houses where it is desired that the electric lights should be lit in the early part of the night and then turned off in the latter part thereof. To do this I 20 provide switch mechanism controlled by two clocks, such as ordinary alarm clocks, one clock being employed to automatically turn on the lights and the other to turn them off. The mechanism is mounted in a suitable 25 casing and the switches are properly insulated from the casing and from each other to prevent accident. The electrical conductors are led in and out through guides of insulating material which effectively prevent short circuits. The feed 30 wires are connected with one of the switches and the lamp wires with the other. Parts of the two switches are connected with each other in such manner that when the two 35 switches are closed, the lights will be lit, but when one of the switches is open, the 40 lights will be extinguished.

In the accompanying drawings:—

Figure 1 is a perspective view of an apparatus embodying my improvements.

Figure 2 is a diagrammatic view showing particularly the switch mechanism and how it is connected with the circuit wires.

Figure 3 is a rear view in longitudinal 50 vertical section, showing the switches set to light the lamps.

Figure 4 is a view similar to Figure 3, showing how the switch mechanism is opened to extinguish the lamps.

55 The switch mechanism may be enclosed in a metal casing A having a hinged door a

and a catch a'. Two alarm clocks are indicated at C, C' which may be held in place by straps C². These clocks may be arranged on the top of the casing or at other suitable parts thereof. The two switches employed are indicated at D and E. These switches are mounted on blocks F of insulating material, such as porcelain, so that they are completely insulated from the box or casing A. The switch D comprises two posts d, d', to one of which is pivoted a blade d² and to the other, a blade d³. These blades, at their outer ends, are connected by a cross piece d⁴ of insulating material. 60 To the cross piece d⁴ is hinged a vertically arranged bar d⁵ having a bent upper end d⁶ adapted to engage the winding mechanism e of the alarm clock C. A spring g tends to lower the bar when released by the 65 key c so as to close the switch.

Circuit wires H, H' enter through blocks I of insulating material arranged in the bottom of the box and these wires are connected to the posts d⁸, d⁹.

The other switch E is constructed and mounted in a similar way. The posts e, e' are secured to the block F. To the post e is pivotally secured a blade e² and to the post e' is pivoted another blade e³. These 85 blades are connected by a cross piece e⁴ of insulating material and to this cross piece is hinged a bar e⁵ having a bent upper end e⁶ adapted to engage the winding key c' of the clock C'. The posts d and e are electrically connected at x, and the posts d' and e' are electrically connected at y.

Referring to Figure 2, the current from the feed wire enters at H and departs at H'. There is no closed circuit through the 95 apparatus when either switch is raised or open. When both switches D and E are closed, the lights will be lit. The closed circuit may be traced as follows (Figure 2): It enters at H, passes from post d⁸ through blade d² to post d, then through connection x to post e, through blade e² to post e⁸, then through supply wires L and L' to post e⁹, then through blade e³ to post e' through connection y to post d', through 100 blade d³ to post d⁹ and out through wire H'.

It will thus be seen that if either switch is open, there will be no current for the lamps.

In using the apparatus, one of the alarm 110 clocks is set to turn on the lights at the desired time, and the other to turn them

off after a predetermined interval. The bar d^5 is made to engage the winding key c of the clock C in the manner indicated in Figure 1, and the switch E is then closed. 5 This clock is preferably used to determine the time when the lights are to be lit. The bar e^6 is made to engage the winding key c' of the clock C', which is set to indicate when the lamps are to be turned off. When 10 the bars d^5 and e^6 are thus set, the switch D is open and the switch E closed and at this time there can, of course, be no closed circuit through the lamps. When the time for the lights to be turned on arrives, the winding 15 key c will release the bar d^5 and the spring g will cause the switch D to close and the circuit through the lamps will be established. The lights will then remain on until the time for opening the circuit arrives, 20 which is predetermined by the clock C' which at this time releases the bar e^6 and the spring g' opens the switch E and the circuit is broken. 25 In the drawings, Figure 1, it will be observed that the alarm mechanism of the clock C is set for six o'clock and the alarm mechanism of the clock C' is set for twelve o'clock. Assuming the store to be closed at five o'clock, the lamps will be automatically 30 lit at six o'clock when the alarm clock C operates. The lights will remain on until twelve o'clock—midnight—when the alarm mechanism of the clock C' operates to open the circuit to extinguish the lights. 35 The apparatus, it will be observed, is extremely simple. It may be set very quickly and requires no great amount of intelligence

to set it, it being a simple matter to set the clocks and to perfect the engagement of the switches with the clocks in the manner before described. Experience has demonstrated that the switch mechanism is absolutely reliable. It may be set when the store is closed in the afternoon or any other time in the day or early evening. The lights 45 will be turned on at the proper time and turned off in due season. The apparatus may be very easily connected with lamp circuits already in use or may be attached when the lights are being installed. 50

I claim as my invention:

Electric time switch mechanism comprising two separately operable circuit controlling switches, a casing enclosing them, a piece of insulating fire-proof material on 55 which the switches are mounted, two clocks mounted on the outside of the top of the casing and secured thereto, a spring associated with one of the switches and tending to open it, another spring associated 60 with the other switch and tending to close it, a rod hinged to one of the switches and extending directly therefrom through the top of the casing and engaging the winding key of one of the clocks to hold said switch 65 open and another similar rod hinged to the other switch and extending directly therefrom through the top of the casing and engaging the winding key of the other clock to hold the associated switch closed. 70

In testimony whereof I have hereunto subscribed my name.

ARTHUR R. ROSAMOND.
